UNITED STATES PATENT OFFICE.

PLINY F. HODGES, OF CHICAGO, ILLINOIS, ASSIGNOR TO HIMSELF AND
WILLIAM DEERING, OF SAME PLACE.

AUTOMATIC GRAIN-BINDER.

SPECIFICATION forming part of Letters Patent No. 252,463, dated January 17, 1882.

Application filed November 10, 1880. (Model.)

To all whom it may concern:

Be it known that I, PLINY F. HODGES, residing at Chicago, in the county of Cook and State of Illinois, and a citizen of the United States, have invented a new and useful Improvement in Automatic Grain-Binders, of which the following is a full description, reference being had to the accompanying drawings, in which—

10 Figure 1 shows an elevation of the binding-arm and crank with the cap or cover removed to show the twister and cutter and their operating mechanisms; Fig. 2, a longitudinal section of the binding-arm on line 1 1 of Fig. 1, 15 showing the cutters and operating mechanism; Figs. 3 and 4, details showing the slide and support for the cutters; Fig. 5, a detail in longitudinal section of the binding-arm, showing the mechanism for operating the 20 twister; Fig. 6, an elevation of the crank detached; Fig. 7, a detail showing the location of the stop-pinions by which the mechanisms of the twister and cutter are operated; Figs. 25 8 and 9, enlarged details of the stop pinions.

This invention belongs to automatic grain-binders in which wire is used as the means for encompassing the bundle, the wire being passed around the bundle by an arm, after which the strands are twisted and the main wire severed to finish the operation; and it relates particularly to the construction, arrangement, and operation of the twisting and cutting devices in their relation to each other and to the movements of the binding-arm, and has for its object to simplify the construction and arrangement of the mechanism which operates these devices, and to insure a positive action of the twister and cutter which will make their operation effectual and certain; and its nature 30 consists in providing a cutting device consisting of shear-blades pivoted together, and having their tails or handle ends operated by pivoted link-connections through the movements of a sliding block carrying the shear-blades, 35 and having a reciprocating movement given thereto by a pitman operated from an eccentric, and a twisting device consisting of a hook operated by an intermittently-revolving shaft and gear-wheels, both actuated by a single 40 crank, having a head or flange provided with

an internal cogged segment and a stop-flange arranged relatively to each other and to stop-pinions which operate the twisting and cutting mechanisms, and so located in reference to the movements of the binding-arm that the 55 twister and cutter will each have a positive action given them by the crank while the arm is finishing its downstroke by the engagement of the cogged segment with the pinions, and will be inoperative during the balance of the 60 movement of the crank and arm by the engagement of the stop-flange with the stops on the pinions; in the peculiar arrangement and location of the mechanisms in relation to each other and to the binding-arm; in the peculiar construction of the binding-arm and crank and their relation one to the other, whereby the 65 crank performs both the office of moving the arm and of actuating the twisting and cutting mechanisms; and in the peculiar construction 70 and arrangement of the shear-blades and their opening and closing devices.

In the drawings, A represents the body of binding-arm; B, the cover; C, the extension; D, the bearing for the crank head or flange; 75 E, the crank head or flange; F, the crank; a, the twister-hook; a', the shank of the hook a; b b', the gear-wheels for revolving the hook a; c, the shaft for driving the gear-wheels b b'; c', the bearings for the shaft c; d d', the gear-wheels for driving the shaft c; e, the shaft of the wheel d'; e', the bearing for the shaft e; f, the stop-pinion for driving the shaft e; f', the stop on the pinion f; g h, the blades of 80 the cutters; g' h', the levers or handles of the cutters; i, the pivot for the cutters; j j', the links for opening and closing the cutters; k k', the pivots for the links; k'', the supports for 85 the links; l, the sliding plate carrying the cutters; l', the guide-pin for the plate l; l'', the ears on the plate l; m, the support or guide for the plate l; m', the slot for the pin l'; m'', the ears or lugs for attachment of the plate m; n, the pitman or rod for operating the plate l; n', the eccentric for operating n; o, the shaft 90 of the eccentric n'; o', the bearing for the shaft o; p, the stop-pinion for driving the shaft o; p', the stop on the pinion p; q, the cogged segment for engaging the pinions f p; q', the stop-flange for engaging the stops f' p'; r, the slot 100

in the binding-arm point for the passage of the binding-wire; *s*, the stop or guide for retaining the cover of the binding-arm; *s'*, the wire-slot in the guide *s*; *t*, the stops against which the binding-wire is drawn; *u u'*, the anti-friction rollers for allowing the binding-wire to draw without injuring the twisting-hook; *v*, the opening in the point of the binding-arm for the discharge of the waste wire and other substances; *w*, the bolt for attaching the crank to the binding-arm, and serving as a pivot or trunnion for the head of the binding-arm crank; *x*, the bearing in the binding-arm for the bolt *w*; *y*, the bearing on the head of the binding-arm crank; *z*, the opening for attaching the crank to a driving-shaft.

As shown, the twister and cutter are located and operate in the point of the binding-arm. The mechanisms for operating them are carried by the arm, and the crank which vibrates the arm also actuates the mechanism; but the devices, with their operating mechanisms, can be attached beneath a binding-table and perform their respective functions, the driving-crank being operated in any suitable manner in unison with the movements of the binding-arm.

The body *A* and extension *C* may be of the form shown in Fig. 1, or any other suitable form for the location of the twister and cutter and their operating mechanism in the body *A*, and for hanging the arm so that it can have a vibratory or reciprocating movement to carry the binding-wire around the bundle. As shown, the body and extension are cast or otherwise formed from a single piece, the extension being somewhat curved, the body enlarged at its upper end, its central portion straight, or nearly so, and its point slightly curved and sharp to enter and pass through the grain for the bundle. The body *A* is provided with a side flange extending from near its extreme point around its entire edge, forming a central cavity, in which are located the twister and cutter, and their operating mechanism, and at the juncture of the crank with the body is an enlargement, *D*, forming a circular plate, which serves as a bearing for the end of the crank which drives the arm.

The cover *B* is cast or otherwise formed into a shape corresponding to the flanged portion of the body *A*, and its entire edge is provided with side flanges coinciding with the side flanges of *A*, so that when the two parts are together an interior chamber is formed for the reception of the mechanism, and a smooth exterior face is presented to allow the passage of the arm through the grain.

The crank by which the binding-arm is reciprocated has a circular head or enlargement, *E*, at the end where the binding-arm is pivoted, which head, as shown, is provided with a flange around its entire circumference, the edge of which bears against the enlargement *D* when the parts are together. The arm or lever portion *F* of the crank is of sufficient length to give the required throw to the binding-arm, and has

an opening, *z*, for attaching the crank to a revolving shaft. The arm is to be suspended by attaching the crank to its shaft and connecting the end of the extension *C*, by a link or otherwise, to a support, so that as the crank revolves the arm will be given a vibrating or reciprocating movement.

The twister may be in the form of a hook, *a*, as shown, or of any other well-known form of revolving twister which will act to twist the strands of wire together and coil the end of the main wire around its shank to hold the wire.

The shank *a'* is mounted in suitable bearings formed on the body *A*, so arranged as to bring the hook in proper position to do its work. As shown, two bearings are provided, one at or near the edge of the body and the other within the body, the upper or cap portion of each being removable and the under formed or cast with the body. Between these bearings, on the shank, is secured a beveled-gear wheel, *b*, which meshes with a beveled-gear wheel, *b'*, of somewhat larger diameter, secured to the lower end of a shaft, *c*, mounted in suitable bearings, *c'*, the upper or cap portions of which are removable, and the under portions are cast or formed with the body *A*. To the upper end of this shaft *c* is secured a beveled-gear wheel, *d*, which meshes with a beveled-gear wheel, *d'*, of larger diameter, secured to a short transverse shaft, *e*, which has its bearing in a projection or boss, *e'*, located on the body *A* in line with the shaft *c*, so that the shaft *e* will properly center with the shaft *c* and come within the interior of the flange on the head *E*. The shaft *e* projects through the body *A*, and to its end is secured a pinion, *f*, which pinion, as shown, has a portion of two of its cogs or leaves cut away so as to leave a plane face, which forms a stop, *f'*, making the pinion a stop-pinion and giving the shaft *c* an intermittent rotary movement. The shaft *c* is located on one side of the body *A*, and its location and the location and arrangement of the beveled gears *d d' b b'*, bearings *c c'*, twister-hook *a*, and its shank *a'* in relation to each other and to the shaft *c* are shown in Figs. 1 and 5, and the location and arrangement of the shaft *e*, bearing *e'*, and pinion *f* in relation to the shaft *c* and the center of motion of the flange of the crank-head are shown in Figs. 1, 5, and 7.

The construction, it will be seen, is very simple, and at the same time it will be found efficient and positive in its action, giving to the twister a positive movement.

The device for severing the wire consists of two cutters or blades, *g h*, having straight cutting-edges properly beveled, and curved handles or levers *g' h'*, each blade and its handle, as shown, being formed from a single piece, the curve of the handles bringing them to the opposite side of their respective blades and crossing the blades and handles, so that when joined together by a suitable screw or pivot, *i*, they work on the plan and principle of a pair of shears. The outer ends of the handles

g' h' are respectively pivoted to the outer or free ends of links j j' by means of suitable pins or pivots, k, which links are of corresponding length, are located opposite each other in parallel planes, and have corresponding movements in the arc of circles of the same radius, and are pivoted at their inner ends, by means of suitable pins or pivots, k', to projections k'', located on opposite sides of the frame m, in line with each other, and at the same distance from the center of the frame, so that the stationary point of pivot of each link will be equidistant from a line passing through the point of pivot of the shear-blades.

15 The slide or head l carries the shears, which are pivoted thereto by the screw pin or pivot i. This slide or head l is located in the frame m, and has a reciprocating movement, which movement advances and recedes the shears, and also opens and closes them through the action of the links j j', the free ends of which are carried inward as the shears descend, carrying with them the handles g' and h' and closing the blades g h, and are carried outward as the shears ascend, carrying the handles with them and opening the blades, making the movements automatic in both directions.

20 The frame m is made or cast from a single piece, so as to have upwardly-projecting flanges, between which is an opening suitable to receive the frame l, which, as shown, is retained in place between the side flanges by the screw or pin l', the shank of which passes through the elongated slot m', formed in the bottom of the frame, into the body of the slide, the slot m' being of sufficient length for the slide to reciprocate; but the slide l may be secured in the frame m in some other suitable manner that will permit of a free reciprocating movement. This frame m is attached, as shown, to the body A by means of screws or bolts, which pass through the ears or projections m'', and is located above the twisting-hook, and so arranged in reference to the hook and the binding-wire that the advance of the shears will bring the blades each side of the wire, and the closing of the blades by the advance will sever the wire outside of the twisting-hook.

25 On the upper end of the slide l are lugs or ears l'', between which is pivoted the lower end of a pitman or rod, n, which extends up and has its upper end provided with an opening to receive an eccentric, n', formed by attaching a circular disk or wheel at one side of its center to a shaft, o, which shaft has its bearing in a projection or boss, o', cast or formed on the body A, so as to bring the shaft within the interior of the flange on the head E. The shaft o extends through the body A, and to its projecting end is secured a pinion, p, having a stop, p', the pinion and stop being similar in form and construction to the pinion f and stop f', (shown in Figs. 8 and 9,) making the pinion a stop-pinion and giving the eccentric n an intermittent rotary movement.

30 The frame m stands edgewise to the body A, and at right angles, or nearly so, to the shank

of the twister, and the pitman n is located opposite the shaft c, and its location and the location of the frame and shears in reference to the twisting-hook are shown in Fig. 1, and the construction and arrangement of the slide, the shears, and the actuating-links are shown in Fig. 2. The location of the eccentric and its shaft and driving-pinion in relation to the driving-pinion f and the driving-gear of the shaft c and the center of motion of the flange of the crank-head is shown in Figs. 1, 2, and 7. This cutting mechanism is very simple in its construction and arrangement, and is positive in 80 its action, as each advance of the slide or head l must close the blades and sever the wire, and the advance must take place whenever the eccentric is revolved.

35 The pinions f p are located and arranged in such relation to the center of motion of the crank and to the interior diameter of the flange on the head of the crank as to be in the arc of a circle struck from the pivot-center and within the interior circumference of the flange. The 90 interior face of the flange is provided with a cogged segment, q, having the requisite number of cogs or leaves to engage the pinions f p and cause them to make one complete revolution in passing the length of the segment. 95 The cogs or leaves of this segment extend from the bottom of the flange to its edge, and extending around the interior of the flange from each end of the segment is a ledge or flange, q', which projects inward in line with the face 100 of the segment and comes in contact with the cut-away portion of the pinions and keeps them from revolving, except when engaged by the segment, the flange being of the requisite depth for the end face of the cut-away leaves of the 105 pinion to ride thereon or clear it, so as not to interfere with the revolving of the head E around its pivot. The pinions f p are so located and arranged with reference to each other and to the cogged segment q that as the head revolves 110 the cogged segment will first engage the pinion f and drive the twister through the shaft c and gear d d' b b', and will pass from that pinion and engage the pinion p and rotate the eccentric n' and advance and recede the shears, 115 by which arrangement the wire will be first twisted or coiled, and then severed at the completion of the twisting or coiling. The locations of the cogged segment and pinions in relation to the movement of the binding-arm and 120 crank are such that the segment will commence to act on the pinion f as the arm is completing its forward or down movement and just before the crank begins its upward movement, and will pass from the pinion p after the crank has 125 commenced its ascent; and the construction and arrangement of these parts enable both pinions and their respective mechanisms to be operated from and by the same driving device on the crank and at the proper time, and insure a perfect and harmonious operation of both devices which will be positive and reliable.

130 The binding-arm is provided with a slot, r, for the passage of the binding-wire into the arm,

so as to be within reach of the twisting and cutting devices, which slot, as shown, is formed partly in the flanges of both the body and cover.

Guides or retainers for keeping the cover and body in proper relation are to be provided, located on the flange of either the cover or the body, one of which, *s*, is shown located just below the frame *m*, and is provided with a slot, *s'*, corresponding to and coinciding with the slot *r* for the passage of the binding-wire.

The stops or shoulders *t* are formed by the face of the flanges at the end of the slots, and limit the passage of the wire into the arm, and in order to prevent breaking or cutting of the wire, they are rounded off, so as to present a circular face for contact with the wire.

The binding arm is pivotally connected with the crank by a pin or bolt, *w*, located at the center of the head *E*, a projection or boss, *y*, being formed at that point, through which and the end of the crank the bolt passes, and is to be firmly secured by any suitable means. This bolt projects beyond the face of the flange on the head, and extends through the projection or boss *x* formed on the body *A*, which forms a bearing therefor, and its projecting end is screw-threaded, so that by means of a nut the crank and arm are pivotally united. The cover and body are to be secured together by bolts or otherwise, the bolts being so located as not to interfere with the operation of the devices located and operating within the arm.

The operation will be readily understood. The binding-wire is carried around the bundle in the usual manner, and as the arm reaches the point where the segment *q* acts on the pinion *f* the binding-arm will have carried the wire so that it is around the bundle and in position in the slot *r* for the twister to catch the two strands of the wire and twist them together, after which the wire is severed by the cutters and the bundle free to be discharged, and this operation will continue till the binding is completed. The binding-wire passes from a spool suitably located for the purpose, and anti-friction rollers *u u'* are provided to take the strain off the wire and prevent it from cutting into the hook. When attached to a binding-table instead of a binding-arm, the parts are to have the same relative arrangement to each other, a suitable casing being provided to receive the twister, cutter, and the operating mechanisms and to locate the crank thereon for driving the mechanisms, the crank having a head similar in construction to the head *E*, and for the same purpose.

In place of the eccentric *n'* might be used a crank located on the end of the shaft *o* and arranged to reciprocate the bar *n*.

What I claim as new, and desire to secure by Letters Patent, is as follows:

1. In combination with the binding-arm of an automatic grain-binder, a twisting-hook, *a*, having a shank, *a'*, and operated by the gear-wheels *b b'*, shaft *c*, and gear-wheels *d d'* from a driving-pinion, *f*, and a cutting device consisting of shear-blades pivoted to a sliding head and operated by a pitman and eccentric from a driving-pinion, *p*, the pinions *f p* both being driven intermittently by the rotation of a single crank, substantially as and for the purposes specified.

2. A wire-cutting device for an automatic grain-binder, consisting of the blades *g h*, having the handles *g' h'*, links *j j'*, pivoted as described, slide or head *l*, carrying the shears and located in a support or frame, and a mechanism for reciprocating the head or slide and advancing and receding the shear-blades to open and close them, substantially as and for the purpose specified.

3. The twisting-hook *a*, having a shank, *a'*, beveled gear *b b'*, shaft *c*, beveled gear *d d'*, stop-pinion *f*, shear-blades *g h*, having handles *g' h'*, links *j j'*, slide or head *l*, frame *m*, pitman or rod *n*, eccentric *n'*, and stop-pinion *p*, located and arranged as described, in combination with the head *E*, located on the end of the crank *F*, and having a flange provided with a cogged segment, *q*, and stop-flange *q'*, for operating the twisting and cutting mechanisms, substantially as specified.

4. A binding-arm consisting of the body *A*, extension *C*, and cover *B*, the body and cover having side flanges to form an interior chamber to receive the twisting mechanism, consisting of the hook *a*, having the shank *a'*, beveled gear *b b'*, shaft *c*, and beveled gear *d d'*, and to receive the cutting mechanism consisting of the blades *g h*, having handles *g' h'*, links *j j'*, slide or head *l*, frame *m*, pitman or rod *n*, and eccentric *n'*, and locate the two mechanisms side by side, and have them operative entirely within the binding-arm, substantially as specified.

PLINY F. HODGES.
